(57) **CLAIM**

The ornamental design for an illumination device for inspection, as shown and described.

DESCRIPTION

FIG. 1 is a front view of an illumination device for inspection. FIG. 2 is a rear view of the illumination device of FIG. 1.

FIG. 3 is a right side view of the illumination device of FIG. 1.

FIG. 4 is a left side view of the illumination device of FIG. 1. FIG. 5 is a top view of the illumination device of FIG. 1.

FIG. 6 is a bottom view of the illumination device of FIG. 1; and,

FIG. 7 is a front perspective view showing the illumination device of FIG. 1, with an electric cable attached thereto. The broken lines shown in the drawings represent an electric cable and form no part of the claimed design.

1 Claim, 5 Drawing Sheets
